UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed December 16, 1929. Serial No. 414,266.

My invention relates to an improvement in slicing machines of the type in which a rotary knife is associated with a work supporting carriage and means for guiding it past the cutting edge and across the face of the knife. One object of my invention is the provision of means for preventing lateral movement of the work upon the carriage. Another object is the provision of guiding means for guiding the work in the path toward the knife. Another object is the provision of laterally adjustable guiding and holding means for engaging the opposite sides of the work upon the carriage. Other objects will appear from time to time in the course of the specification and claims.

I illustrate my invention more or less diagrammatically in the accompanying drawings, wherein—

20 Figure 1 is an elevation;

Figure 2 is a section on the line 2—2 of Figure 1;

Figure 3 is a plan view;

25 Figure 4 is a section on the line 4—4 of Figure 2; and

Figure 5 is a section similar to Figure 4 of a modification.

Like parts are indicated by like symbols throughout the specification and drawings.

30 Referring to the drawings, A generally indicates any suitable base or frame member mounted for example upon yielding supports or studs A¹. Mounted on the frame is any suitable driving means the details of which do not form of themselves any part of the present invention. I illustrate, however, a driving belt B passing about a pulley B¹ upon the knife shaft B². B³ indicates the rotary knife having a forward depression B⁴

35 in which seats the arcuate edge B⁶ of the forward guard plate B⁵. It will be understood that the axis of the knife is preferably horizontal and is tilted somewhat out of perpendicularity to the guard plate B⁵, in order that the cutting edge may extend forwardly of the guard plate.

40 C generally indicates any suitable gauge plate mounted for example upon the gauge plate support C¹ and adapted to be actuated, as by the manual control knob C², whereby

the gauge plate may be moved into and out of the cutting plane and may be set at any desired adjustment, to control the thickness of the slices. It will be observed, as in Figure 2, that the gauge plate is somewhat bowed, 55 as at C³, to conform to the arc of the cutting plane caused by the tilting of the knife axis. The guard and gauge plates lie in generally parallel planes.

D¹ indicate tracks upon the frame A, 60 along which is slidable the carriage structure generally indicated as D². Tiltably mounted upon the carriage D² is the work engaging or supporting member D³ which may be pivoted as at D⁴ and which may be held in tilted 65 adjustment, as by the links D⁵ slotted as at D⁶. D⁷ is any suitable locking knob adapted to lock the links in position, D⁸ being washers adapted to engage the sides of the links. D⁹ indicates any suitable guide pin or track 70 associated with the carriage, and preferably mounted upon or supported upon the member D³. Movable therealong is any suitable pusher plate which is not indicated herein as not forming of itself any part of the present invention and as not necessarily being employed with the structure.

E indicates a guide shaft or pin extending along the edge of the member D³ remote from the cutting plane. Slidable therealong is the 80 sleeve E¹ the bore of which is grooved as at E² as shown in Figures 2 and 4. E³ E⁴ are springs positioned within said grooves and operative between the opposed faces of the pin E and the sleeve E¹. Preferably these 85 springs are of such strength as to permit movement of the sleeve along the pin in response to positive thrust, but to resist any tendency of the sleeve to shift upon the pin except in response to a positive thrust. It 90 will be understood that the sleeve is rotatable about the pin as well as slidable along it. Associated with the sleeve is the guide member E⁴ extending towards the cutting plane, and generally perpendicular to the planes of 95 gauge and guard plate. It may be secured to the sleeve E¹, as by being screwed as at E⁵ to the extension or lug E⁶ of the sleeve. E⁷ is a downward projection from the lower edge 100 of the member E⁴ whereby its outer end may

be supported upon the member D³, it being in general preferable that the rest of the lower edge of the member E⁴ be held out of contact with the face of the member D³. As will be seen by the dotted line position of the member E⁴ in Figure 2 it may be swung out of position and out of vertical alignment with the face of the member D³. Also, as shown in Figure 3, I preferably provide an extension D¹⁰ of the member D³, whereby the member E⁴ may be moved laterally out of vertical alignment with the face of the member D³. It will be seen, as in Figure 3, that the right hand end of the pin E extends somewhat to the right of the right-hand edge of the member D³. For example the end of the pin may be mounted upon the bracket D¹².

At the left-hand edge of the member D³, in the position in which it is shown in Figures 2 and 3, is a fixed guide or stop or abutment member G. It may terminate at its inner edge in the upward extension G¹ associated with the guard member G² which serves to mask the cutting edge of the knife when the carriage is at the termination of its cutting excursion.

Referring to Figure 5 it illustrates a form of control means for the member E⁴ which differs somewhat from that shown in Figure 4. The bar E is therein shown as notched as at E²⁰ in opposition to the trigger or dog E²¹, which may be employed to maintain a positive contact with the said notches, in order to hold the member E⁴ against movement. E²² indicates a spring whereby the member E²¹ may be held in locking engagement with the notches E²⁰, and E²³ is a manually controlled lever whereby the member E²¹ may be lifted against said spring E²².

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In slicing material upon a slicing machine of the class herein shown it is desirable to prevent lateral movement of the work upon the carriage and to constrain the work to movement toward the cutting plane. The work may be fed forwardly toward the cutting plane either by a pusher plate or by direct manual contact. Where a pusher plate is employed of a width sufficiently great to extend substantially across the member D³, it is necessary to remove the pusher plate when the member E⁴ is adjusted to positions more closely adjacent the fixed abutment G than the width of the pusher plate. I find

in practice that it is important to prevent lateral movement of the work for several reasons. For one reason, if the work is clamped between two abutments, it is always solidly positioned against the fixed abutment G. In such case, when the work is moved into contact with the cutting edge of the knife, the drag on the work is at a minimum and a clean, square slice is taken. When cutting such relatively soft materials as meat loaf or some of the softer sausages a cleaner slice is cut and the slice is cut more easily. The relatively soft substance is more or less compressed or guided between two abutments which engage its opposite sides. An adjustable abutment is also of use in constraining round articles, such as the harder sausages, from rolling upon the flat face of the support D³. It is not always practical to tilt the support in order to hold such articles by gravity against the abutment G. It is quicker to move the movable abutment or member E⁴ into contact with a bit of sausage than it is to tilt the whole support D³ into position to hold the sausage by gravity against the abutment G.

Since it is not always desirable to use the movable member E⁴, it may be moved into the dotted line position, as shown in Figure 3, in which case the entire surface of the member D³ is exposed for use, either with or without the pusher plate. When de-crusting bread or de-rinding bacon, it is even possible to swing the member E⁴ into the position in which it is shown in Figure 2, in which case it does not interfere with the de-rinding or de-crusting operation.

I claim:

1. In a slicing machine having a knife and means for actuating it, a work supporting carriage and means for guiding it across the face and past the cutting edge of the knife, and a plurality of work guides upstanding above the surface of the carriage and generally perpendicular to the path of movement of the carriage, one of said guides being freely slideable, in relation to the carriage, along a path generally parallel with the path of movement of the carriage, and guiding means for said work guide, including a track member mounted upon said carriage along the edge remote from the cutting plane and below the plane of the work supporting portion of the carriage, a sleeve slideable along said track member, and a rigid supporting connection between said sleeve and said guide.

2. In a slicing machine having a knife and means for actuating it, a work supporting carriage and means for guiding it across the face and past the cutting edge of the knife, and a plurality of work guides upstanding above the surface of the carriage and generally perpendicular to the path of movement of the carriage, one of said guides being freely

- slidable, in relation to the carriage, along a path generally parallel with the path of movement of the carriage, and guiding means for said work guide, including a track member mounted upon said carriage along the edge remote from the cutting plane and below the plane of the work supporting portion of the carriage, a sleeve slidable along said track member, and a rigid supporting connection between said sleeve and said guide, and frictional means associated with said sleeve, operating automatically to prevent unintended movement of the sleeve along the guide.
3. In a slicing machine having a knife and means for actuating it, a work supporting carriage and means for guiding it across the face and past the cutting edge of the knife, and a plurality of work guides upstanding above the surface of the carriage and generally perpendicular to the path of movement of the carriage, one of said guides being freely slidable, in relation to the carriage, along a path generally parallel with the path of movement of the carriage, and guiding means for said guide, including a track member mounted upon said carriage laterally of the edge remote from the cutting plane, a sleeve slidable along said track member, and a supporting connection between said sleeve and said guide, said track member extending a sufficient distance beyond the edge of the carriage which faces the cutting edge of the knife when the carriage is at the beginning of the cutting stroke, to permit the work guide to be moved laterally beyond said edge of the carriage.
4. In a slicing machine having a knife and means for actuating it, a work supporting carriage and means for actuating it across the face and past the cutting edge of the knife, and a plurality of work guides upstanding above the surface of the carriage and generally perpendicular to the path of movement of the carriage, one of said guides being freely slidable, in relation to the carriage, generally parallel with the path of movement of the carriage, and guiding means for said guide, including a track member mounted upon said carriage along the edge remote from the cutting plane, a sleeve slidable along said track member, and a supporting connection between said sleeve and said guide, said sleeve and guide being rotatably mounted in relation to said track member.
5. In a slicing machine having a knife and means for actuating it, a work supporting carriage and means for guiding it across the face and past the cutting edge of the knife, and a plurality of work guides upstanding above the surface of the carriage and generally perpendicular to the path of movement of the carriage, one of said guides being slidable, in relation to the carriage, along a path generally parallel with the path of movement of the carriage, guide means positioned along the edge of said carriage remote from the cutting plane of the knife and extending beyond the edge of said carriage that leads to a cutting stroke, a rigid supporting means by which said slidable work guide is connected to said guide means, bearing means carried by the slidable work guide remote from said guide means engaging the work supporting face of the carriage, and an extension carried by the carriage on said leading edge and cooperating with that portion of the guide extending beyond said leading edge to support the slidable work guide laterally of the work supporting portion of the carriage adjacent said leading edge thereof.
- Signed at Indianapolis, county of Marion, and State of Indiana, this 19th day of November, 1929.
- WILLIAM J. CAMPBELL.
